US0D1110279S

(12) **United States Design Patent** (10) **Patent No.:** **US D1,110,279 S**
(45) **Date of Patent:** **** Jan. 27, 2026**

(54) **CONTACT PIN FOR INTEGRATED CIRCUIT TESTING**

(71) Applicant: **Johnstech International Corporation**, Minneapolis, MN (US)

(72) Inventor: **Melissa Hasskamp**, Minneapolis, MN (US)

(73) Assignee: **Johnstech International Corporation**, Minneapolis, MN (US)

(**) Term: **15 Years**

(21) Appl. No.: **29/941,010**

(22) Filed: **May 7, 2024**

(57) **CLAIM**

The ornamental design for a contact pin for integrated circuit testing as shown and described.

DESCRIPTION

FIG. 1 is a top front right side perspective view of a contact pin for integrated circuit testing showing my new design. FIG. 2 is a bottom rear left side perspective view thereof. FIG. 3 is a front view thereof. FIG. 4 is a rear view thereof. FIG. 5 is a left view thereof. FIG. 6 is a right view thereof. FIG. 7 is a top view thereof; and, FIG. 8 is a bottom view thereof.

1 Claim, 6 Drawing Sheets
